SUN SHADE

Edward C. Hallock, Summit, N.J.

Application July 26, 1956, Serial No. 42,403

Term of patent 14 years

(Cl. D21—6)

I claim:

The ornamental design for a sun shade, as shown.
